UNIVERSAL SUPPORT FOR LIGHT FIXTURES

Abe S. Zagel, Chicago, Ill.

Application April 6, 1938, Serial No. 200,505

1 Claim. (Cl. 240—78)

This invention relates to a universal support for light fixtures, and has, for one of its principal objects, the provision of a support for light fixtures or electric lamps which is so constructed that it can be readily applied to practically any ceiling fitting now in use without the necessity of any special fittings or other arrangements or devices which have heretofore been considered necessary in constructions of this type.

One of the important objects of the invention is to provide a light fixture adapted for supporting a transparent globe in a simple yet efficient manner and one which can be readily assembled in position without the use of special tools or other fittings.

Another important object of the invention is to provide, in an electric light fixture or the like, means for passing a pull cord or chain from an operating switch in the interior of the structure down through the fitting or support for the transparent globe whereby the switch may be operated in a convenient manner and whereby, at the same time, unsightly fittings and other appurtenances will be eliminated.

Another and still further important object of the invention is the provision of a universal fitting or support for electric light housings or structures which is adapted for immediate use in practically any situation and which will eliminate the necessity of drilling or tapping holes in either the original support or the fitting itself and which, furthermore, can be installed without the use of additional tools or special equipment.

Other and further important objects of the invention will be apparent from the disclosures in the accompanying drawing and following specification.

The invention, in a preferred form, is shown in the drawing and hereinafter more fully described.

In the drawing:

Figure 1 is a side elevation, parts being broken away, of the improved universal support for light fixtures of this invention.

Figure 2 is a bottom plan view of the structure of Figure 1, the light globes and transparent cover being removed.

Figure 3 is a top plan view of the structure of Figure 1, showing certain of the universal attachment fittings.

Figure 4 is a detail sectional view of the structure of the preceding figures, showing the same as applied to one type of support which is in common use.

As shown in the drawing:

The reference numeral 10 indicates generally the main supporting plate of the improved universal globe fitting of this invention, the same having a surrounding rim or the like 12 which 5 may be either separate from or integral with the plate 10 and mounted on the plate are two or more electric light sockets 14 of the usual construction. Wires 16 lead into the socket 14, and these wires pass upwardly through openings 18 10 in the plate 10 running to suitable connections in the ceiling.

It has been found in practice that the fittings in the ceiling such as the fittings shown in 20 in Figure 4 are of varied and various types, shapes, 15 dimensions and constructions so that, in many instances, it becomes necessary to rearrange or even substitute a lamp support in order to accommodate a particular type of ceiling fitting which has been installed in either a new or an 20 old dwelling or other building.

One particular type of attachment is illustrated at 22 in Figure 1, this comprising a cylinder entirely open at its top end and closed at its lower end except for a small central hole to allow the 25 screw 24 to pass through. The cylinder 22 is interiorly screw-threaded and is adapted to fit the correspondingly screw-threaded end of gas pipe or the like which is sometimes placed in ceilings for this particular purpose. This element 22 is held in place by means of a screw 24 30 as best shown in Figure 3 so that it can be removed if desired.

In Figure 4, the device of Figure 1 is shown as applied to a different type of ceiling fitting 20 35 which ordinarily comprises a box-like structure having holes drilled and tapped therein for the reception of machine screws or the like 26. It often happens that these holes are in different positions depending upon a particular type of 40 housing or box 20, and obviously unless the structure 10—12 is drilled to correspond to the locations of the holes in the element 20, its ready installation will be accordingly delayed or rendered 45 difficult, is not actually necessitating the substitution of a different type of support or fitting.

To this end, I have provided slotted openings 30 in the plate 10 as best shown in Figures 2 and 3, these openings having enlarged ends as illustrated at 32, these enlarged ends being preferably circular and of a size to accommodate the head of an ordinary machine screw 26. The slotted openings 30 are of sufficient length so that the distance between screws 26 can be readily varied, thereby enabling the device of this invention to 55

accommodate itself or to be readily applied to a connection box 20 of practically any type, size or design. An additional opening 34 is also provided to be used in the case of extremely odd-sized supports.

Also mounted on the plate 10 either by means of the screw 24 or by spot welding or in any other convenient or desired manner, is a combination switch support and transparent globe holder, this comprising an angular bracket member 36 as best shown in Figure 1, having an auxiliary inwardly extending shelf element 38 upon which an electrical switch of any ordinary type is adapted to be supported.

15 A pull chain 42 extends downwardly from the switch 40 and through a hollow fitting 44 which comprises an exteriorly screw-threaded tube adapted to be positioned in a correspondingly screw-threaded opening in the lower end of the element 36.

Also adapted to be mounted on the screw-threaded tube 4 is an interiorly screw-threaded element 46 having associated therewith a flat washer 48 which last-named fittings, in turn, 25 act to support a transparent globe or the like 60 in position with regard to the supporting plate 10-12.

In addition to providing a universally mounted support for the light globe and bulbs, the globe 30 itself is readily accommodated and maintained in desired position on the support while further provision is made for the passage of the switch pull cord through the globe-holding element, thereby providing a neat and attractive 35 unit.

It will be seen that herein is provided a uni-

versal light fixture mounting which is admirably adapted for ready application in old or new buildings and which can be interchangeably fitted into practically any type of support or foundation element regardless of the age or 5 style and which, at the same time, does not require any other equipment except the ordinary supporting screws and a screw-driver for applying the same. Additionally, the novel form of combination switch mounting and globe holder, 10 and particularly as associated with the centralized aperture for the switch pull cord, provides a distinctively novel and attractive and useful construction which proves definitely useful.

15 I claim as my invention:

A universal support for lighting fixtures, comprising a base plate, a plurality of slots in the base plate, each slot adapted to receive attaching means from any type of outlet box, sockets 20 attached to the base plate, a bracket having upper and lower flanges and a central shelf, a switch supported on the shelf, means to attach the upper flange of the bracket to the center of the base plate, a globe enclosing the sockets, 25 switch and bracket, a tubular screw-threaded element screw-threadedly associated with the lower flange of the bracket, a globe retaining element operating on the tubular screw-threaded element to hold the lower part of the globe 30 against the lower flange of the bracket and the upper part of the globe against the base plate and a switch pull cord operating through the tubular screw-threaded element.
